UNITED STATES PATENT OFFICE

151,908

DESIGN FOR PULPWOOD TONGS OR SIMILAR ARTICLE

Maurice M. McElderry, Duluth, Minn.

Application May 24, 1947, Serial No. 139,250

Term of patent 14 years

(Cl. D93—4)

To all whom it may concern:

Be it known that I, Maurice M. McElderry, a citizen of the United States of America, residing at Duluth, in the county of St. Louis and State of Minnesota, have invented a new, original, and ornamental Design for Pulpwood Tongs or Similar Article, of which the following is a specification, reference being had to the accompanying drawing, forming part thereof.

In the drawing:

Fig. 1 is a top plan view of pulpwood tongs or similar article, showing my new design,

Fig. 2 is a side elevational view of Fig. 1, and
Fig. 3 is a bottom plan view of Fig. 2.

I claim:

The ornamental design for pulpwood tongs or similar article, as shown.

MAURICE M. McELDERRY.
